UNITED STATES PATENT OFFICE.

M. G. FARMER, OF SALEM, MASS., ASSIGNOR TO WM. F. CHANNING.

IMPROVED ELECTRO-MAGNETIC FIRE-ALARM APPARATUS.

Specification forming part of Letters Patent No. 22,553, dated January 11, 1859.

To all whom it may concern:

Be it known that I, MOSES G. FARMER, of Salem, in the county of Essex and State of Massachusetts, have invented a new and useful Apparatus or Mechanism which I have called a "Telegraphic Fire-Alarm Signal-Box," and of which the following is a full, clear, and exact description, reference being had to the accompanying drawings, making part of this specification, in which is represented one of the signal-boxes, the door being opened to show the parts within.

In a magnetic fire-alarm system contrived to telegraph the existence of a fire in any part of a city to a central station, any person capable of manipulating a Morse telegraphic instrument could, by means of such instrument—an electro-magnetic circuit, and a suitably-arranged apparatus at the central station—telegraph thereto the exact locality of a fire. In order, however, that prompt notice may be given to the central station of any fire that may take place, it is necessary that the city be divided into a great number of districts or sub-districts, and that there be a telegraphing or signaling station in each of such sub-districts; but it will, manifestly, not be practicable to have a telegraphic operator constantly upon the alert at each of the stations of a large city, and the object of my invention is to enable any person of ordinary intelligence to signalize from any station the occurrence of a fire near that station; and my invention consists of an apparatus placed within the electro-magnetic circuit consisting of a circuit-wheel having certain pins or projections upon its periphery, in connection with a key so arranged that as the circuit-wheel is revolved the circuit shall be closed and broken, and thus a definite signal shall always be sent to the central station corresponding to the station from which the alarm is given, the circuit-wheel to be furnished with means for turning it, whether this be a crank upon its shaft by which it may be turned by hand, or by suitable connections with a spring, which may be wound up temporarily a sufficient distance to turn the circuit-wheel. In the latter case the motions of the circuit-wheel should be regulated by a fly or otherwise.

The mechanism which I have contrived, and which I will now proceed to describe, consists, first, of a circuit-wheel and the means of

actuating it and regulating its motion; secondly, of the means by which the signal indicated upon the circuit-wheel is transmitted to the central station.

In the accompanying drawings the circuit-wheel is indicated at *a*. Its shaft carries a pinion (not seen in the drawings) which engages with a wheel, *b*, upon the shaft of which is a pinion which engages with a wheel, *c*, running loosely upon the shaft *d*. The latter is so connected with this shaft by means of a ratchet-wheel, *f*, and a click, *e*, that when the shaft *d* is revolved by moving its handle *B* in the direction of the arrow 1 the shaft, together with the ratchet-wheel attached to it, shall move independently of the wheel *c* and its click; but when the handle *B* is moved in a direction contrary to its arrow the ratchet-wheel *f*, engaging with the click, shall drive the wheel *c* in the direction of the arrow 2, and, through the connections already explained, the circuit-wheel *a* in the direction of its arrow 3.

The wheel *c* is prevented from moving in a direction contrary to the arrow 2 by the detent *g*. The shaft *d* carries a spring, *C*, the outer end of which is attached to the frame-work *A*, and which is so arranged that as the handle *B* is moved in the direction of its arrow, into the position indicated in red, the spring is wound up, and as it recoils it returns the handle *B* to its position at rest against the plate *D*, and at the same time revolves the wheel *c* and the circuit-wheel in the direction of their arrows, the motion of the circuit-wheel being regulated as follows: The shaft of the circuit-wheel has a wheel, *h*, which engages with a pinion, *i*, upon the shaft *m* of a fan the vanes of which are adjustable so as to retard more or less the velocity of the circuit-wheel. The circuit-wires enter the box and proceed one to the screw-cup *F*, thence to the electro-magnet *G*, thence to the metallic plate *D*, thence to the insulated metallic piece *k*, thence by the key *H* to the metallic frame-work *A*, thence by the wire *l* and screw-cup *I* out of the box. The piece *k* being insulated, if the key *H* be raised into contact with its anvil *p* the circuit will be broken; but when the mechanism is at rest the key *H* is retained in contact with the piece *k* by a spring, *n*, and the circuit remains unbroken.

The circuit-wheel *a* has upon its periphery certain teeth, varying in number, size, or ar-

angement in each box, the circuit-wheel of each station having its specific number or arrangement of teeth. These teeth, as the circuit-wheel revolves, strike against a tooth, *s*, projecting from the under side of the key *H*, by which means this key is raised from off the metallic piece *k* and dropped upon it again, and a signal corresponding with the motions thus imparted to the key *H* is transmitted to the central station, where the circuit-wires terminate.

The armature *r* of the magnet *G* is pivoted at *t*, and is drawn away from the magnet by the spring *L*. Attached to this armature is a hammer, *O*, which, when the armature is released from the magnet strikes against the side of the box, or a small bell within it, and gives a distinctly audible sound.

The wires of the circuit pass in a manner similar to that above described through every signal-box in the circuit; and it is obvious that if the current be interrupted in any one of the boxes between the piece *k* and the key *H* the circuit will be broken at this point, and should the current by any means be thus permanently interrupted and the attempt be made to transmit a signal from any one of the other boxes in the circuit it would fail. This interruption of the current through the boxes may be occasioned by the accumulation of dust upon the piece *k* beneath the key *H*. Should this occur the whole circuit would be thrown out of operation; and in order that the circuit may be complete without passing through the piece *k* and key *H* in all the boxes of the circuit, except in the one from which the signal is being sent, the following device is employed:

M is a metallic spring, which is in electric connection with the plate *D*. *N* is a spring in similar connection with the frame-work *A*. The springs are so arranged that when the door of the box is open they do not come in contact; but when the door is closed it strikes against the pin *w*, projecting from the spring *N*, and presses the latter against the spring *M*, there being sufficient space between the latter and the wooden shelf *R* to permit the spring *M* to yield as the door closes.

The electric current has two ways by which it can pass through all those boxes which are closed—the one already indicated through the piece *K* and the key *H*, and the other from the magnet *G* to the plate *D*, thence, by the springs *M* and *N*, to the frame *A*, and by the wire *t*, as before, out of the box. When, however, the door of the box is opened the spring *N* leaves the spring *M* and the current has but one course, as before indicated, from the piece *k* to the key *H*.

Operation: The above-described signal-boxes are placed at the police-stations, engine-

houses, or even at the corners of the streets, there being one signal-box for each sub-district or station into which the city is divided, the circuit-wheel of each signal-box having its own peculiar arrangement of pins or teeth upon its periphery, as before described, that it may be instantly known at the central station from which sub-district the alarm proceeds. On the occurrence of a fire in any part of the city a fireman, policeman, or any other person intrusted with a station-box key, repairs to the nearest box and opens the door. The contact between the springs *N* and *M* of this box being thus broken, the electric current passes through this box by way of the piece *k* and key *H*. By means of the knob *B* the handle upon the shaft *d* is revolved over into the position seen in red, by which the spring *C* is wound up sufficiently to give the circuit-wheel thirty or forty turns, more or less. The knob *B* is then released, and as the spring runs down the handle returns to its original position of rest upon the plate *D*. The circuit-wheel thus revolved transmits the alarm to the central station, from which the general alarm is given upon the fire-bells of the city. The operator at the central station now telegraphs back to the station that the alarm was received, which is indicated by the blows of the hammer *O* upon the box or bell. This same hammer is also employed to signalize to all the signal-boxes of the city the number of the sub-district or station from whence the alarm was received. The key *H* may be manipulated by hand, and thus any message may be transmitted from the different station-boxes to the central station.

In lieu of employing the motive power of a spring to actuate the circuit-wheel the crank may be placed directly upon the shaft of this wheel, which may then be turned moderately by hand a sufficient number of times to transmit the alarm as before. In such case the fan for regulating the motion of the circuit-wheel would also be dispensed with.

What I claim as my invention, and desire to secure by Letters Patent, is—

1. The circuit-wheel *a* and the crank or handle by which it is actuated, in combination with the key *H* and the electro-magnetic circuit, operating in the manner substantially as set forth, to send a definite signal from a sub-district to the central station.

2. The method of completing the circuit when the door of the signal-box is closed, through the springs *M* and *N*, as set forth, for the purpose described.

MOSES G. FARMER.
